(57) **CLAIM**

I claim the ornamental design for an electrical equipment for ablative treatment, as shown and described.

DESCRIPTION

FIG. 1 is a rear perspective view of an electrical equipment for ablative treatment;

FIG. 2 is another rear perspective view of the electrical equipment for ablative treatment;

FIG. 3 is a front view of the electrical equipment for ablative treatment;

FIG. 4 is a rear view of electrical equipment for the ablative treatment;

FIG. 5 is a front perspective view of the electrical equipment for ablative treatment;

FIG. 6 is another front perspective view of the electrical equipment for ablative treatment;

FIG. 7 is a side view of the electrical equipment for ablative treatment;

FIG. 8 is a side view of another side of the electrical equipment for ablative treatment;

FIG. 9 is a top view of the electrical equipment for ablative treatment; and,

FIG. 10 is another front perspective view of the electrical equipment for ablative treatment.

The broken lines showing environment in FIG. 10 are for illustrative purposes only and form no part of the claimed design.
